Des. 237,972
Patented Dec. 9, 1975

237,972

FAN FOR INTERNAL COMBUSTION ENGINES

Bern M. Bonifant, Tacoma, Wash., assignor to
Flex-A-Lite Corporation, Tacoma, Wash.

Filed Feb. 26, 1975, Ser. No. 553,159

Term of patent 14 years

Int. Cl. D15—01; D23—04
U.S. Cl. D23—165

Fig. 1.

Fig. 2.

Fig. 3.

Fig. 4.

FIG. 1 is a front elevational view of a fan for internal combustion engines showing my new design;

FIG. 2 is a rear elevational view thereof;

FIG. 3 is a side elevational view thereof, looking directly at the end of one fan blade; and

FIG. 4 is a side elevational view thereof, the fan being rotated approximately 36° from its position in FIG. 3.

I claim:

The ornamental design of a fan for internal combustion engines, substantially as shown.
